CAM GRINDING MACHINE

Herbert A. Silven, Worcester, Mass., assignor to
 Norton Company, Worcester, Mass., a corporation of Massachusetts

Application August 14, 1936, Serial No. 96,077

19 Claims. (Cl. 51—101)

This invention relates to grinding machines, and more particularly to an automatic camshaft grinding machine.

One object of this invention is to provide a simple and thoroughly practical machine for automatically grinding a plurality of cam blanks on an integral camshaft. A further object of this invention is to provide an automatic cycle control mechanism for controlling the feeding movement of the grinding wheel, the positioning movement of the work table, and the rocking movement of the cam toward and from the grinding wheel to grind successive cam blanks automatically to a predetermined size and contour. Another object is to provide an automatic cycle control mechanism in which a main control valve is actuated in timed relation with the wheel feeding movement. A further object is to provide an electrically controlled hydraulic mechanism for controlling the main control valve which in turn controls the admission of fluid to the table positioning cylinder and the rock bar cylinder.

A further object of the invention is to provide a combined wheel feeding and pilot valve which serves to shift a main control valve to control the cycle of operations of the machine. Another object of the invention is to provide an electrically operated mechanism to actuate the pilot valve after a predetermined cycle of operation to move the various parts of the machine into position for grinding the next cam, or which may be manually operated after a given cycle of operation to position the parts for grinding the next cam on the camshaft. Another object is to provide a mechanism to render the cycle control mechanism inoperative during the longitudinal movement of the table. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of the possible embodiments of the mechanical features of this invention,

Fig. 1 is a front elevation of an automatic cam grinding machine embodying this invention;

Fig. 2 is a diagrammatic view showing the piping diagram and electrical control circuit;

Fig. 3 is a fragmentary front elevation, on an enlarged scale, of the control mechanism;

Fig. 4 is a fragmentary cross sectional view, taken approximately on the line 4—4 of Fig. 3;

Fig. 5 is a fragmentary cross sectional view through the machine, taken approximately on the line 5—5 of Fig. 1, showing the electrical and manual control for the wheel feed and pilot valve;

Fig. 6 is a fragmentary sectional view, taken approximately on the line 6—6 of Fig. 5, showing the connections between the manual and electrical controls for the wheel feed and pilot valve;

Fig. 7 is a right-hand end elevation, on an enlarged scale, of the cycle control mechanism with the cover removed; and

Fig. 8 is a fragmentary plan view, on an enlarged scale, of the main control lever for starting the cycle of operation.

A cam grinding machine has been illustrated in the drawings having a base 10 which supports a longitudinally movable work table 11 on the usual flat way (not shown) and V-way 13. The base 10 also supports a transversely movable wheel slide 15 on ways (not shown) for a transverse feeding movement toward and from the work supporting table 11. The wheel slide 15 supports a rotatable grinding wheel 16.

The longitudinally movable work table 11 supports a pivotally mounted rock bar 18 which is supported in bearings 19 and 20 on the table 11 (Figs. 1 and 2) and is arranged so that it may be rocked about an axis which is parallel to the axis of the grinding wheel 16. The rock bar 18 is provided with a rotatable headstock spindle 22 and a headstock center 23. The rock bar 18 also supports a footstock 24 having a footstock center 25. The headstock center 23 and the footstock center 25 are arranged to rotatably support a camshaft 26 to be ground.

35

Master cams and roller

In order that the cams on the camshaft 26 may be ground to a predetermined size and contour, it is desirable to provide a series of master cams 28 for controlling the rocking movement of the rock bar 18 so as to rock the camshaft 26 being ground toward and from the periphery of the grinding wheel 16 so as to generate a predetermined shape thereon. A plurality of master cams 28 are mounted on the headstock spindle 22 in axial alignment with the axis of the camshaft 26 being ground. A master cam roller or follower 29 is slidably mounted on a rotatable shaft 30 which is rotatably supported in brackets 31 and 32 (Fig. 1). The master cam roller 29 is preferably indexed automatically as the table 11 is moved longitudinally to position the master cam roller 29 opposite the master cam 28 which corresponds to the cam being ground on the cam shaft 26. The details

40

25

55

of the master cam roller indexing mechanism have not been illustrated since this feature is not considered part of the present invention. For a detailed disclosure of the automatic shifting of the master cam roller, reference may be had to the prior United States Patent No. 1,783,755 to Trefethen and Belden and also to the United States Patent No. 2,022,178 to Belden and Silven dated November 26, 1935.

10

Table traverse

The work supporting table 11 is moved longitudinally relative to the base 10 by means of a fluid pressure operated mechanism comprising a cylinder 39 which is fixed to the base 10. A piston 40 is slidably mounted within the cylinder 39 and is connected by means of a piston rod 41 with a bracket 42 depending from table 11. Fluid under pressure may be admitted either 20 through a pipe 43 into a cylinder chamber 44 to cause the piston 40 and the table 11 to move toward the right (Fig. 2), or it may be admitted through a pipe 45 into a cylinder chamber 46 to cause the piston 40 and the work supporting 25 table 11 to move toward the left (Fig. 2). The admission of fluid under pressure to the cylinder 39 is controlled by a valve mechanism to be hereinafter described.

30

Wheel feed

The wheel slide 15 may be moved transversely on the base 10 by a wheel feeding mechanism which may be actuated either manually or hydraulically, as desired. In the preferred construction, the wheel slide 15 is provided with a depending nut 58 meshing with a rotatable feed screw 51 which is rotatably supported in the base 10 and is connected so that it may be rotated by a manually operable feed wheel 52 on the front 40 of the machine base 10. The feed screw 51 is arranged so that it may be moved bodily in an endwise direction rapidly to move the grinding wheel slide 15 and the grinding wheel 16 either toward or away from the work. This is preferably accomplished by connecting the rearward end of the feed screw 51 with a piston rod 53 which carries a piston 54 slidably mounted within a cylinder 55. The fluid pressure wheel feeding mechanism may be supplemented by a hydraulically operated dash pot feed controlling mechanism (not shown). This dash pot mechanism may be arranged as shown in the patent to Silven No. 2,023,704 dated December 10, 1935. The dash pot feed control mechanism has not been 55 illustrated in the present application, since this feature is not considered a part of the present invention. For further details of the dash pot construction, reference may be had to the above-mentioned patent. By utilizing a dash pot mechanism of this type, the wheel may be advanced rapidly by admitting fluid under pressure through a pipe 56 into a cylinder chamber 57 to move the wheel slide 15 rapidly up to a position where the wheel 16 is about to contact with a cam to 65 be ground. Then the dash pot piston is picked up by the piston rod 53 and the further advance of the grinding wheel in grinding the cam is controlled by the exhausting of fluid from the dash pot cylinder.

In order to remove the grinding wheel from contact with the work after the cam has been ground to a predetermined size and contour, the admission of fluid under pressure to the cylinder 55 is reversed and fluid is admitted through a 75 pipe 58 into a cylinder chamber 59. A control or

reversing valve 60 is provided to control the admission of fluid to the cylinder 55. In the position of the parts (Fig. 2), fluid under pressure from a tank or sump 61 within the base 10 passes through a pipe 62 and is forced under pressure 5 by a pump 63 through a pipe 64 into a valve chamber 65 which is located between the valve pistons 66 and 67. In the position of the valve 66 (Fig. 2), fluid under pressure entering the valve chamber 65 passes outwardly through the 10 pipe 58 into the cylinder chamber 59 to cause the piston 54 to move rearwardly or toward the right (Fig. 2) to withdraw the wheel slide 15 and the grinding wheel 16 from operative engagement with the work and into an inoperative position.

During the rearward movement of the piston 54, fluid exhausts from the cylinder chamber 57, through the pipe 56, through a V-port 68, into a valve chamber 69, between a valve piston 70 and the valve piston 66 and through a passage 71 and 15 exhausts through a pipe 72 into the reservoir 61. When it is desired to cause an approaching movement of the grinding wheel 16, the valve 60 is shifted so that fluid under pressure passing 20 through pipe 64 enters the cylinder chamber 65 and passes out through V-port 68 and pipe 56 into cylinder chamber 57 to cause the piston 54 to move toward the left (Fig. 2) and thereby 25 cause the wheel slide 15 and the grinding wheel 16 to be moved transversely toward the camshaft 26 to be ground. During the forward feeding 30 movement of the grinding wheel, fluid is exhausted from the cylinder chamber 59, through pipe 58, and passes through a V-port into a valve chamber 75 located between the valve piston 67 and a valve piston 76, and through the passage 71 and the exhaust pipe 72, into the reservoir 61.

Rock bar actuating mechanism

In order that the master cams 28 may be maintained in operative engagement with the master cam roller 29 during the grinding operation on a cam, a yieldable pressure device is provided which serves to yieldably maintain the master cam 28 in contact with the follower roller 29. As shown 40 in the drawings, the rock bar 18 is provided with an arm 77. A cylinder 78 is pivotally supported on the bracket 31 by means of a circular 45 clamping band 79. The cylinder 78 contains a piston 80 which is connected by a piston rod 81 with a stud 82 on the arm 77. A spring 83 surrounds the piston rod 81 and is contained within the cylinder 78 between the piston 80 and a head (not shown) which is fixed in the lower 50 end of the cylinder 78. The spring 83 is compressed to a sufficient extent to maintain the master cam 28 in operative contact with the master cam roller 29 during the grinding operation.

Hydraulic actuation—rock bar

A fluid pressure mechanism is provided to rock the bar 18 to an inoperative position automatically before the table 11 is traversed, so that the master cam 28 and follower 29 and product camshaft 26 and grinding wheel 16 will be separated before the traversing of the table 11 is started. This mechanism may comprise a fluid pressure cylinder 85 having a piston 86 slidably mounted therein. The piston 86 is connected to a piston rod 87 arranged to contact with the 70 arm 77. When fluid under pressure is admitted through a pipe 89 into a cylinder chamber 90 within the cylinder 85, the piston 86 moves downwardly and contacts with the arm 77 to rock the rock bar 18 and separate the master cam 28 75

from the follower roller 29. A valve in the pipe line 89 may be regulated to control the downward movement of the piston 86.

Grinding wheel driving mechanism

The grinding wheel 16 may be driven from any suitable source of power, such as a driving motor (not shown) mounted either on the base of the machine or on the floor adjacent to the machine, as shown in the above-mentioned prior Patent No. 2,022,173, to which reference may be had for disclosure of the wheel driving mechanism. This feature is not considered a part of the present invention and consequently has not been illustrated in detail.

Table indexing movement

The table 11 is traversed or indexed longitudinally and automatically by means of a fluid pressure system, above described, which comprises a cylinder 39 containing a piston 40 which is connected by a piston rod 41 with the depending bracket 42 on the table 11. The admission of fluid to either cylinder chamber 44 or 46 is controlled by a table controlling or reversing valve 91. Fluid from the pump 63 passes through a pipe 92, through a pipe 93, into a valve chamber 94 between valve pistons 95 and 96. The pipe 45 is connected between the valve 91 and the cylinder chamber 46, and a pipe 43 is connected between the valve 91 and the cylinder chamber 44. It will be readily apparent from this disclosure that when the table reversing valve 91 is in the position illustrated in Fig. 2, no fluid is admitted to either of the cylinder chambers and the table 11 will remain stationary. The valve 91 is provided with a valve stem 97 which is operatively connected to a manually operable control lever 98 mounted on a rock shaft 99. A short lever 100 is mounted on the rear end of the rock shaft 99 and has a pin 101 engaging a spool 102 on the valve stem 97. It will be readily apparent from this construction that when the lever 98 is moved in a clockwise direction, the valve stem 97 will be moved toward the left, as viewed in Fig. 2, so as to admit fluid under pressure through the pipe 43 to the cylinder chamber 44, and cause a movement of the table 11 toward the right (Figs. 1 and 2). Similarly, the valve stem 97 moves toward the right (Fig. 2) so as to pass fluid through the pipe 45 into the pipe 46 to move the table 11 toward the left (Figs. 1 and 2).

The lever 98 is normally held in a broken line position 98a or 98b by means of an arrow point 105 on the lever 100 which is engaged by a spring-pressed roller 106. The lever 98 is in a broken line position 98a, while the table 11 is indexed intermittently in a direction toward the right (Figs. 1 and 2). The lever 98 is in the broken line position 98b (Fig. 3), while the table 11 is being indexed toward the left, as indicated in Figs. 1, 2 and 3. The valve stem 97 is normally held in a position to admit fluid through the pipe 43 or the pipe 45 to the cylinder 39. The admission of fluid through the pipe 93, to the valve 91, is controlled by a main control valve, as will be hereinafter described.

An actuating mechanism is provided for the valve so that movement of the work supporting table 11 operates to close the valve 91 so that when the table is traversed through a predetermined distance to position the next cam on the product camshaft 26 in operative relation with the grinding wheel 16, the valve 91 is automatically closed to stop further table movement.

This is preferably accomplished by means of a dog bar 110 which is adjustably mounted on the front edge of table 11 by means of bolts in elongated slots. The dog bar 110 is provided with elongated slot 111 which serves to support and guide a plurality of adjustable dogs 112. The dogs 112 may be adjusted along the bar to conform with the spacing of the cams on the camshaft 26 to be ground. The dog bar, if necessary for any variation in successive camshafts, may be adjusted longitudinally of the table without upsetting the adjusting of the individual dogs. In order that the control lever 98 may be moved in the direction of the movement of the table 11, it is necessary to provide a secondary actuating lever 114 for cooperating with the table dogs. As illustrated in the drawings, a dog lever 114 is pivotally mounted on a stud 115. The lower end of the dog lever 114 is provided with a projecting pin 116 which rides in a cylindrical aperture 117 in the lever 98.

Assuming the lever 98 is positioned as shown in Fig. 3, that is in a neutral position for starting of the grinding cycle, with the dog lever 114 in contact with the table stop dog 113 which is adjustably mounted on the table 11, the lever 98 is thrown either manually or automatically into position 98a to move the valve stem 97 and admit fluid through pipe 43 into cylinder chamber 44 to start the movement of the table 11 in a direction toward the right, as viewed in Figs. 1, 2 and 3. This movement traverses the camshaft 26 supported by the table 11 to move the first product cam on the shaft 26 into operative relation with the grinding wheel 16. The traversing movement continues until the dog lever 114 is engaged by the first dog 112. The dog lever 114 is rocked into the position illustrated in Fig. 3, swinging the pin 116 into engagement with an adjustable stop screw 118, or if the table 11 is indexed to the left, with an adjustable stop screw 119, both of which are adjustable with relation to the lever 98. When the table 11 is indexed to the right, the lever 98 swings from the position 98a into the full line position 98, as illustrated in Fig. 3, with the arrow point 105 depressing the spring-pressed roller 106. The parts, however, are adjusted so that the arrow point 105 does not reach the high point on the spring pressed roller 106, so that the roller is at all times exerting a pressure tending to move the lever 98 either in a clockwise or counterclockwise direction. The swinging of the lever 98 from position 98a into full line position, as indicated in Fig. 3, moves the valve stem 97 into the position as illustrated in Fig. 2, cutting off fluid under pressure from both of the pipes 43 and 45, thereby stopping the movement of the work carrying table 11. By adjusting the position of the dogs 112 along the dog bar 110, the stopping position of the table 11 may be adjusted, as desired, so that the product cams will be positioned successively in operative relation with the grinding wheel.

The dog lever 114 is slidably mounted on the stud 115 so that it may be thrown out of the path of the table dogs 112 to permit a further traversing movement of the table 11. A lever 120 is pivotally mounted on a stud 121 and at its upper end is formed as a yoke having opposed pins 122 and 123 engaging slots in opposite sides of a hub 124 on the dog lever 114. When the lever 120 is moved from the full line position (Fig. 2) and rocked in a clockwise direction, the dog lever 114 is moved rearwardly or toward the right (Fig. 2) on the stud 115, out of the path of the table dogs 112, 75

so that the table 11 may be indexed to position the next cam in operative relation with the grinding wheel. A spring 125 normally maintains the dog lever 114 in alignment with the table 11 dogs 112 during the indexing traverse of the table 11. This movement is preferably accomplished in timed relationship with the other operating mechanisms of the machine. A fluid pressure cylinder 127 is mounted within the 10 machine base and is provided with a piston 128 having a piston rod 129 engaging an end 130 of the lever 120. A spring 131 which surrounds the piston rod 129 serves normally to retain the piston in its rearward or inoperative position. 15 Fluid under pressure is admitted through a pipe 132 into a cylinder chamber 133 in timed relationship with the other operating mechanisms of the machine, to rock the lever 120 in a clockwise direction (Fig. 2) and thereby slide the dog lever 114 into an inoperative position out of alignment 20 with the table dogs 112. This mechanism is preferably connected to a main control valve which will hereinafter be described so as to be operated automatically in timed relation with the 25 other movements of the machine.

When the table 11 is indexed longitudinally, the longitudinal movement thereof continues until a table dog 112 engages the dog lever 114 and rocks the dog lever and, through the connecting 30 parts, the control 98, so that the arrow point 105 rides up on the spring pressed roller 106 until the control lever 98 assumes the full line position as shown in Fig. 3, in which position the table 35 control or reverse valve 91 is in a neutral or stop position, cutting off fluid under pressure from the cylinder chambers 44 and 46 of the table cylinder 39.

Table pilot valve

40 After the table 11 has been indexed intermittently for grinding successive cams on the camshaft 26, it is then desirable to shift the table index control valve 91 into a reverse position so that the arrow point 105 rides on the opposite 45 side of the axis of the spring pressed roller 106. This is preferably accomplished by means of a pilot valve 135 which is of a balanced piston type and is normally held in a neutral or inoperative position by means of a spring 136. When the 50 table reaches its end position in its movement toward the left, a depending projection on an adjustable truing dog 137 mounted on the table 11 (Figs. 1 and 3) engages the upper end of a pilot valve lever 138 and rocks it so as to move 55 a valve stem 139 toward the right, as viewed in Fig. 2, so as to admit fluid which enters through a pipe 140 and a valve chamber 141 into a pipe 142 which passes fluid under pressure into a valve chamber 143 at one end of the table reversing valve 91. This pressure moves the valve 60 stem 97 so that the control lever 98 and the arrow point 105 pass over the high point on the spring pressed roller 106 and shifts the valve 91 into a reverse position, so that after truing of the grinding wheel the table 11 is ready for an 65 intermittent traversing or indexing movement in a direction toward the right, as viewed in Figs. 1, 2 and 3.

Wheel truing mechanism

70 In a machine of this type, it is desirable that the grinding wheel be trued automatically in between operations so that a trued grinding wheel face will be presented at the start of each grinding operation. A truing apparatus comprising 75 a bracket 145 is fixedly mounted on the table 11

and carries a truing tool which may be adjusted relative to the bracket 145 by means of a micrometer mechanism 146. The details of the truing mechanism have not been illustrated in detail, since this feature is not considered part of the present invention. For further details of this mechanism, reference may be had to the U. S. patent to Belden and Silven No. 2,022,178 dated November 26, 1935. After the last cam on the shaft has been ground, the wheel moves to an extreme rearward position with the piston 54 engaging the rear end of the cylinder 55 (Fig. 2). The table is then given an additional traversing movement to carry the previously adjusted diamond or truing tool across the operative face of the grinding wheel 16, while it is in its extreme rearward position.

Slow traverse—truing

The normal traversing or indexing movement of the table is comparatively rapid to reduce the loss of time between successive grinding operations. The normal table speed is not at all suited for a truing operation which requires a very slow, uniform relative traversing movement between the truing tool and the grinding wheel. To obtain a slow traversing movement of the table, a suitable slow feed or throttle valve 150 is provided. When fluid is exhausted from the cylinder 39 through either pipes 43 or 45, it passes through either a valve chamber 151 or 152, pipes 153 or 154 respectively, and then through a valve chamber 155 or 156 in the pilot valve 135 and through a common exhaust pipe 157 which enters a valve chamber 158 in the feed control valve 150. A V-port 159 normally is wide open, permitting unrestrained exhaust of fluid from the cylinder 39. When the table 11 indexes or traverses from the last cam on the camshaft and moves toward a truing position, a depending cam surface 162 on the truing dog 137 strikes a roller 163 which is mounted on the upper end of a spring pressed plunger 164. The lower end of the plunger engages a rock arm 165 mounted on the outer end of a rock shaft 166. The other end of the shaft 166 carries a rock arm 167 which is connected by a pin 168 to move a valve stem 169 of the slow speed valve 150. When the cam surface 162 moves the roller 163 downwardly, it rocks the shaft 166 and arm 167 and the valve stem 169 moves a valve piston 170 toward the right (Fig. 2) to partially close the V-port 159, thereby restricting the exhaust of fluid from the table traversing cylinder 39 so as to produce a slow traversing movement of the table 11 and the diamond or truing tool across the operative face of the grinding wheel 16.

At the same time the slow speed valve moves to throttle the exhaust of fluid to cause a slow truing movement of the table 11, a pipe 171 is uncovered by movement of a valve piston 172 to admit fluid under pressure from a pipe 185 through a valve chamber 173 into the pipe 171, into a cylinder chamber 191, to actuate a lever 192 and thereby stop the wheel spindle reciprocation during the truing operation. The table continues its truing movement toward the left until the pilot valve lever 138 engages a depending projection on the adjustable truing dog 137 to move the pilot valve 135 from a neutral position and admit fluid under pressure into the valve chamber 143 of the table traverse valve 91 to reverse the direction of movement of the table. The table moves slowly to pass the diamond across the face of the grinding wheel on its return stroke. The slow

movement continues until the roller 163 rides up the cam surface 162 on the dog 137 as the table approaches the first cam on the camshaft 26 into position for starting the next grinding cycle.

5 A spring 197 connected between the lever 167 and a stud 198 on the valve stem 150 serves to return the valve stem 169 to its normal position so as to uncover the pipe 171 to allow fluid to exhaust from the cylinder chamber 191, through the pipe 10 171, a valve chamber 199, a pipe 200, a pipe 201, into the reservoir 61, thus allowing a spring 202 to swing the lever 192 to start the wheel spindle reciprocation for grinding the next camshaft. At the same time, the V-port 159 is uncovered and 15 unrestricted exhaust of fluid from the table traverse cylinder 39 starts the table 11 moving at its normal traversing or indexing speed.

While the apparatus shown is set to pass the truing tool across the face of the wheel once in 20 each direction, it is possible to adjust the truing dog 137 so that a cam actuated star wheel will provide a greater number of passes of the diamond across the operative face of the grinding wheel, if desired. Details of construction of 25 the truing dog have not been illustrated in the present case, since this feature is not considered part of the present invention. Reference may be had to the prior United States patent to Bel- 30 den and Trefethen No. 2,022,178 dated November 26, 1935 for details of disclosure of the truing dog.

Main control valve

In a machine of this type, the mechanisms function automatically to successively grind a 35 plurality of cam blanks on a camshaft to a pre-determined size and contour, and it is essential that all of the mechanisms be properly timed. Inasmuch as most of the mechanisms of the 40 machine are controlled by fluid pressure mechanisms, it is desirable to provide a main control valve 175 therefor, having a valve stem 174 formed integral with a hollow valve member having valve pistons 176, 177, 178, 179, 180, 181 and 182 formed integrally therewith. Fluid under pressure 45 from the pump 63 passes through the pipe 92 into a valve chamber 183 in the main control valve 175. Fluid under pressure passes from the valve chamber 183 through the pipe 185 to the slow speed or throttle 50 valve 150. Fluid under pressure from the valve chamber 183 also passes through a central aperture 186 extending longitudinally within the main control valve. Fluid from the passage 55 186 enters a valve chamber 187 and passes out through the pipe 93 into the valve chamber 94 of the traverse or table index control valve 91. At the same time, fluid under pressure passing through the central aperture 186 passes into a 60 valve chamber 188 and out through the pipe 132 into cylinder chamber 133 to move the dog lever 114 out of the path of the table dogs 112.

Wheel feed—cycle pilot valve

In order that the main control valve 175 may 65 be shifted to control the cycle of operation as desired, a valve is provided to actuate the main control valve. In a grinding machine, while the grinding wheel is in grinding contact with the work piece, there is more or less spring in 70 the various parts of the machine. Any sudden change in direction of movement of the moving parts of the machine or the sudden shifting of fluid pressure within the system may be sufficient to set up a vibration which causes the wheel to vibrate and thereby to produce inac- 75

curacy in the work piece. It is one of the objects of this invention to provide a control mechanism whereby the grinding wheel 16 is removed from operative contact with the cam being ground before the longitudinal shifting of the work table 5 11 or the rocking of the rock bar 18 to an inoperative position. This is preferably accomplished by utilizing the grinding wheel feed control valve 68 as a control valve to control the admission of fluid to the wheel feed cylinder 55 and also to 10 serve as a cycle pilot valve whereby fluid under pressure passes through the pipe 64 into the feed control valve chamber 65. In the position of the parts as illustrated in Fig. 2, fluid under pressure passes out through the pipe 58 and a pipe 232 15 into a chamber 233 at the right-hand end of the main control valve 175 and serves to move the main control valve 175 into the position illustrated in Fig. 2.

A spring 234 serves normally to hold the wheel feed valve stem 235 to the right, as illustrated in Fig. 2, so that fluid under pressure entering the feed control and pilot valve chamber 65 passes out through the pipe 58 into the wheel feed cylinder chamber 59 to cause a rearward movement of 25 the grinding wheel 16 and also passes through the pipe 232 into the chamber 233 to normally hold the main control valve 175 in the position as illustrated in Fig. 2. When the main control valve 175 is moved into the position illustrated 30 by fluid passing through the wheel feed valve 60, fluid is exhausted from a chamber 236 at the left-hand end of the valve 175, forcing fluid out through a pipe 237, through a valve chamber 69 in the wheel feed and cycle pilot valve 60, and out 35 through the passage 71 and the pipe 72 into the reservoir 61.

A solenoid 240 is provided to actuate the valve 60 in one direction. As previously described, the solenoid 240 is connected by a link 241 and a stud 242 with a rock arm 243 which is pivotally mounted on a stud 244. The upper end of the rock arm 243 is provided with a pin 238 which engages a spool shaped member 239 on the end of the stem of valve 60, as illustrated in Figs. 2 and 6, and 45 serves when energized to shift the wheel feed valve 60 into the reverse position. In this position of the valve pistons, fluid under pressure from the pipe 64 entering the valve chamber 65 passes through the pipe 56 into wheel feed cylinder chamber 57 to cause a forward feeding movement of the grinding wheel 16 and at the same time passes fluid under pressure through pipe 237 into the end chamber 236 of the main control valve 175 to move the main control valve stem 50 174 toward the right (Fig. 2). This movement of the control valve 175 serves to admit fluid under pressure to the various mechanisms of the machine. The solenoid 240 is preferably connected, in a manner to be hereinafter described, 55 to control the movement of the wheel feed valve 60 which in turn controls the admission of fluid to shift the main control valve 175 after a predetermined time in the grinding cycle.

This movement of the control valve 175 admits 65 fluid under pressure through the pipe 132 into the cylinder chamber 133 to shift the dog lever 114 out of the path of the table dogs 112. When the dog lever 114 moves out of the path of the table dogs 112, the released tension of the spring- 70 pressed roller 106 serves to again shift the main control lever 98 into a broken line position 98a so that when the main control valve is again shifted into the position illustrated in Fig. 2, fluid will be admitted through the pipe 93 and the pipe 43 75

into chamber 44 to cause an indexing movement of the table 11. During the wheel feeding movement, when fluid under pressure is admitted through pipe 237 into chamber 236 at the end of 5 the main control valve 175 to shift the main control valve 175 into a position toward the right (Fig. 2), the valve piston 176 covers the pipe 93 and thereby prevents fluid under pressure from passing into the table reversing valve 91 or to the 10 table operating cylinder 39.

Cycle control mechanism

In order to obtain the maximum efficiency from the machine, it is desirable to provide a 15 suitable cycle control device which serves, after a cam has been rotated through a predetermined number of rotations in operative contact with the grinding wheel, to actuate the main control valve 175 and thereby to admit fluid under pressure to 20 the cylinder chamber 90 to rock the master cams 28 and the product cams 26 away from the grinding wheel 16 and the master cam roller 29 respectively, and to admit fluid to the cylinder chamber 59 to move the grinding wheel 16 rearwardly to an inoperative position, and then to admit fluid under pressure to the table traverse cylinder 39 automatically to index the table 11 to present the next cam 26 to be ground into 25 operative relation with the grinding wheel 16. 30 This is preferably accomplished by means of a cycle control counting device 245 which is contained within a rectangularly shaped box on top of the bracket 31.

The counting device comprises a ratchet wheel 35 246 which is mounted to rotate on a shaft 247. A pawl 248 is carried by a stud 249 on an arm 250 which is connected to move with a lever 251 so that the two arms 250 and 251 operate as a bell crank. The arm 251 is connected by an adjustable link 252, to the lower end of which is connected a stud 82 on the arm 77 which is fixed to the rock bar 18. Each time the rock bar 18 rocks in a clockwise direction toward the grinding wheel, the bell crank lever 250-251 serves to 40 rock the pawl 248 idly over the teeth of the ratchet wheel 246, and when the rock bar 18 is rocked by the master cams in a counterclockwise direction (Fig. 2) away from the wheel, it serves to cause a downward movement of the link 252, 45 and the bell crank 250-251 serves to cause the pawl 248 to turn the ratchet wheel 246 a predetermined adjustable amount each time the rock bar moves through its rocking movement. The shaft 247 also carries an adjustable striker arm 50 55 253 which is arranged in the path of a lever 254 which serves to rock a support 255 which is mounted pivotally on a stud 256. The arm 255 carries a mercury switch 257. When the ratchet wheel 246 has been rotated through a predetermined extent, the striker arm 253 engages the projection 254 and rocks the arm 255 about its supporting stud 256 and trips the mercury switch 257. The tripping of the mercury switch serves 60 to close the circuit and to energize the relay 260 65 which in turn closes a circuit to energize the solenoid 240 to shift the wheel feed valve 60 and thereby admit fluid under pressure to shift the main control valve 175 toward the right (Fig. 2). 70 It will be readily apparent from the foregoing 75 that each time the rock bar 18 is oscillated in grinding a cam, the link 252 serves through the bell crank lever 250-251 to oscillate the pawl 248 to cause a movement of the ratchet wheel 246. The link 252 is provided with adjustable nuts 262 and a spring 263 by means of which

the effective length of the link 252 may be adjusted to give the desired action to the pawl 248. The extent of movement of the pawl may be controlled by means of an adjusting screw 264 which contacts with bracket 31, carried by the 5 arm 251, so that between the adjustment of the nut 262 and the screw 264, the extent of movement of the pawl may be adjusted as desired.

It is desirable to provide an adjustable cycle control mechanism which is arranged so that the grinding cycle may be changed readily without changing the speed of movement of the operating parts. This may be accomplished by adjusting the extent of movement of the ratchet pawl so that the grinding cycle may be shortened or lengthened, 10 as desired, without changing or affecting the speeds of the operating parts of the machine. In order that the extent of movement of the pawl 248 may be readily varied to permit adjustment of the number of ratchet teeth picked up at each 15 actuation of the pawl 248, it is desirable to provide a means for readily adjusting the length of the arm 251. The arm 251 is provided with a slot 265, and the link 252 is adjustably clamped in the desired location within the slot 265 by 20 means of a clamping device 266. By adjusting the position of the clamping device 266 within the slot 265, the effective length of the lever arm 251 25 may be varied to adjust the extent of actuation of the pawl 248.

After a cam has been ground to a predetermined extent, it is desirable to provide a suitable mechanism for withdrawing the pawl 248 from the ratchet wheel 246 to reset the mechanism for controlling the grinding of the next cam blank. This is preferably accomplished by providing a solenoid 267 which is provided with an upwardly extending rod 268 having a pair of adjustably mounted pins 269 and 270 which are arranged to engage a lever 271 which is formed as an extension of the ratchet pawl 248. A spring 272 surrounds the upper extension of the rod 268 and is interposed between the casing 245 and the nuts 273 which are screw threaded into the upper end of the rod 268. A spring 274 is connected to a stud 275 on a rotary member or hub 276 which carries the ratchet wheel 246. The other end of the spring is connected to a stud 277 on the upper corner of the control box 245. It will be readily apparent from the foregoing disclosure that when the solenoid 267 is energized, as shown in Fig. 2, the rod 268 is pulled downwardly against the tension of the spring 272 and serves to rock the lever 271 and the pawl 248 to disengage the pawl 278 from the ratchet wheel 246. When the pawls disengage the ratchet wheel 246, the released tension of the spring 274 serves to rotate the member 276 and the ratchet wheel 246 into its initial position, as illustrated in Fig. 2, so that the lower surface of the ratchet engages the adjustable stop 261 55 so that the mechanism is ready to control the grinding of the next cam blank.

Work rotation

The headstock spindle 22 may be rotated by 65 any suitable driving mechanism, such as an electric motor 280 which is connected through a suitable gear mechanism to rotate the work driving center 23 at the desired speed. In the preferred construction, a two-speed work drive is provided, 70 such as that shown in the prior patent to Belden et al. No 2,022,178 dated November 26, 1935, to which reference may be had for details of disclosure. A manually operable lever 281 serves to 75 move a clutch member 282 into engagement with

the clutch members 283 and 284 to rotate the work driver at either a proper speed for rough grinding or for finish grinding, depending upon the operation for which the machine is set up. 5 Details of the gear drive between the headstock motor 280 and the center 23 have not been illustrated in the present case, since they are not considered part of the present invention. For a detailed disclosure of this mechanism, reference 10 may be had to the prior United States Patent No. 2,022,178.

Start and trip lever

A start and trip lever 290 is pivotally mounted 15 on the lever 217. The lever 290 is arranged to swing in a substantially horizontal plane and is provided with a projecting lug 292 which is arranged to engage an extension of the pin 122 on the pivotally mounted lever 120. When the lever 20 290 is moved toward the right (Fig. 3, the lug 292 engages pin 122 and rocks the lever 120 about its pivot 121. This movement serves to move the dog lever 114 out of the path of the table stop dog 113. This movement allows the lever 100 to move 25 in a clockwise direction due to the pressure of the spring pressed roller 106 on the arrow head 105 so as to move the valve stem 97 toward the left (Fig. 2) so as to admit fluid from the pipe 93 into valve chamber 94 and out through the pipe 43 into the 30 table cylinder chamber 44 to cause the piston 40 and the table 11 to move toward the right, as viewed in Figs. 1 and 2. As soon as the dog lever 114 passes the table stop dog 113, the spring 125 rocks the lever 120 in a counterclockwise direction 35 (Fig. 4) so that the dog lever 114 moves back into the path of the table dogs 112. Movement of the table 11 toward the right continues until the dog lever 114 engages the first table dog 112 to position the first cam on the camshaft 26 to be ground 40 in operative relation with the grinding wheel 16. This movement rocks the lever 98 and the lever 100 to shift the valve stem 97 into the position illustrated in Fig. 2, so that the valve piston 95 cuts off the flow of fluid to pipe 43, thereby stopping 45 the movement of the table 11.

After the start lever has been shifted toward the right (Fig. 3) to shift the dog lever 114 out of the path of the table stop dog 113 and start the table traversing movement or grinding cycle, 50 the lever 290 is shifted back by means of the pin 122 contacting the lug 292 so that dog lever 114 will be able to contact with the first table dog 112 but not closing the limit switch 299. However, when the table is stopped by the first table 55 dog, lever 290 is moved towards the left to close the limit switch 299 to energize solenoid 240 to operate the wheel feed valve 60. This serves to move the pin 294 carried by the lever 290 into position 294a out of the path of the surface 295, 60 which serves to allow a lever 296 to rock about its supporting stud 297 and allow the rod 298 of the limit switch 299 to move upwardly to close the circuit and render the mercury switch operative. Closing the limit switch serves to energize a relay 65 260 which in turn makes a circuit to energize the solenoid 240 which shifts the wheel feed valve 60 into the reverse position from that shown in Figs. 2 and 6, so that fluid entering the feed valve chamber 65 passes outwardly through the pipes 70 56 and 237 to move the main control valve 115 toward the right and also to start the forward advance of the grinding wheel 16 and its supporting wheel slide 15 (Fig. 2) to permit the exhaust of fluid from the rock bar cylinder chamber 75 90 so as to allow the rock bar 18 to rock in a

clockwise direction (Fig. 2) toward the grinding wheel 16 so that the master cam 28 engages the master cam roller 29.

The grinding wheel 16 continues its forward feeding movement to grind the cams on the cam-shaft 26 to the desired size and contour and the wheel 16 then recedes, after which fluid is admitted to the wheel feed cylinder 55 to chamber 53 to cause a rearward movement of the grinding wheel 16. 10

A normally closed limit switch 305 is arranged so that its actuating roller 307 is released by movement of the lever 98 in the position of the parts as illustrated in Fig. 2 and closes the limit switch 305 to energize the solenoid 267 to return 15 the ratchet wheel 246 to its initial position. When the dog lever 114 is shifted out of the path of the table stop dog 113, the lever 98 moves in a clockwise direction into the position 98a which serves to shift the valve stem 97 to position the valve 91 20 for the next table traverse. At the same time the lever 98, which engages the roller 307 of limit switch 305, is rocked in a clockwise direction to break the circuit and thereby deenergize a relay 306 which in turn deenergizes solenoid 267 to 25 render the ratchet pawl carried by the lever 250 and the ratchet pawl 278 of the cycle control mechanism 245 operative. The ratchet pawls remain in engagement with the ratchet wheel 246 during the indexing movement of the table 11, the 30 lever 98 being in the position 98a (Fig. 3), and the limit switch 305 being open to make the solenoid 267 inactive. 35

When the work table 11 reaches the extreme position to the right, it is desirable to open the 35 limit switch 299 so that the solenoids 240 and 267 are deenergized. This is preferably accomplished by providing a dog 308 on the table 11. The dog 308 is arranged in the path of a vertical plunger 309 which is connected to a lever 296 which cooperates with the rod 298. The lever 296 is pivotally supported on a stud 297 and arranged so that when the dog 308 depresses the plunger 309, the lever 296 swings in a counterclockwise direction to depress the rod 298 and the 45 limit switch 299, which serves to open the switch, thereby rendering the cycle control mechanism 245 inoperative. 45

The dog 308 engages the plunger 309 and is depressed. The table reversing dog 318 rocks the 50 lever 138 which actuates the pilot valve 135 to cause the reverse valve 91 to reverse the movement of the table 11. This action rocks the lever 98 from position 98a to position 98b which allows the dog lever 114 to clear the table dogs 112 so 55 that the table 11 will move to the truing position. This is accomplished by lever 98 contacting the adjustable screw 310 carried by a swinging lever 311 mounted on the stud 312. Lever 311 carries a latch 313 which rides on a pin 314 carried by 60 the lever 98. During the indexing movement of the table 11 after the grinding operation, the lever 311 assumes the position it has at the start of the grinding cycle. When the lever 98 swings the lever 311 from the full line position (Fig. 3) 65 to allow dog lever 114 to clear the table dogs 112 on the return stroke, the table stop dog 113, being of a pivotally mounted type allowing swinging in a counterclockwise direction only (Fig. 2), will let the dog lever 114 pass by, and upon completion of the truing operation will stop the table 11 in a loading position. In the last truing 70 pass, the lever 98 is in the position 98a, and through pin 314 which contacts latch 313 to swing lever 311 to the full line position so that 75

the dog lever 114 will move by means of a spring 125 into further contacting relation with the table stop dog 113 at the end of a complete grinding cycle.

5 In order to prevent the grinding wheel from moving forward during the table traversing movement, the table 11 is provided with a series of dogs 308a which are mounted on an adjustable bar 221 carried by the adjustable dog bar 110 and arranged to engage the plunger 309 and to open the limit switch 299 to render the cycle controlling mechanism 245 inoperative during the traversing movement between product cams. By varying the length of the stop dogs 308a, the 15 cycle controlling mechanism 245 may be rendered inoperative during the traversing past a main bearing where the distance between cams on the camshaft 26 is greater than the spacing of the cams.

20 *Manual-cycle control*

In the grinding of certain types of camshafts, it may be desirable to provide a machine in which the cycle of operation may be fully automatic so 25 that all of the cams on the shaft will be ground without attention on the part of the operator, as shown and described above. It may be desirable, however, to so arrange the mechanism that, if desired, the cycle of operation may be manually 30 controlled; that is after a cam has been ground, a manually operable lever is arranged to automatically separate the wheel and work, rock the rock bar to an inoperative position, and index the table longitudinally to present the next cam 35 into operative relationship with the grinding wheel. Such a construction has been illustrated in Figs. 1, 5 and 6 of the drawings. A manually operable control lever 330 is pivotally mounted on a stud 331 carried by a bracket 332 fixed on 40 the front of the machine base 10. The control lever 330 is formed as a bell crank, the lower short arm of which carries a stud 333 which is connected to one end of a link or connecting rod 334, the outer end of which carries a detachable coupling 335. One end of a link 336 is pivotally connected by a stud 337 with the lever 243, and the other end is detachably connected by the coupling 335 with the rod 334. It will be readily apparent from this construction that when a connecting pin 338 connects the links 334 and 336, 45 a manual movement of the lever 330 will operate through the rock arm 243 to shift the wheel feed valve 60 in either direction, depending on the direction in which the lever 330 is moved. In case 50 it is desired to operate the machine under a manually controlled cycle, the cycle control counting mechanism switch 316 is opened, thereby rendering the solenoid 240 inoperative. The pin 338 is inserted, as illustrated in Fig. 5, so that 55 the wheel feed valve 60 is controlled by the manually operable control lever 330 so that after the wheel 16 has been advanced toward the cam and ground a cam to a predetermined size, movement of the control lever 330 in a clockwise direction 60 (Fig. 5) serves to shift the control valve 60. The shifting of the control valve 60 serves to admit fluid under pressure to the cylinder chamber 59 to cause a rearward movement of the grinding wheel 16 and at the same time serves to pass fluid under pressure to shift the main control valve 175, to admit fluid under pressure to the rock bar cylinder 85 to rock the bar and camshaft to an inoperative position, and also to admit fluid under pressure to the table traverse cylinder 39 to index 70 the table 11 to position the next cam on the cam- 75

shaft 26 into operative relation with the grinding wheel 16.

In case it is desired to operate the machine with an automatic cycle control to automatically 5 grind all of the cams on a shaft without attention on the part of the operator, the pin 338 is removed, thereby disconnecting the links 334 and 336 to render the manually operable lever 330 inoperative. The switch 316 is then closed and the machine may be operated under automatic cycle 10 control.

Operation

Assuming the table 11 to be in its extreme left-hand or loading position, the machine is started 15 into operation by first pushing an electric control button (not shown) to start the rotation of the grinding wheel 16, then pushing a second button (not shown) to start the rotation of the fluid pump 63. Push button 315 is closed to prepare for 20 the rotation of the work driving motor 280. The work piece, such as a camshaft 26, is then loaded into the machine and supported between the headstock center 23 and the footstock center 25. The work driving clutch is then engaged by shifting the lever 281 to engage the movable clutch member 282 with either the clutch member 283 or 25 284, depending upon whether a finish grinding or rough grinding speed of the work is desired. The cycle control push button 316 is then closed to 30 render the mercury switch 257 operative so that the machine is then under the control of the cycle counting mechanism 245. The hand lever 290 is then moved toward the right (Fig. 3). This movement serves to rock the lever 290 about its 35 vertical supporting stud so that the lug 292 engages the pin 122 to rock the lever 120 about its pivot 121 to move the dog lever 114 out of the path of the table stop dog 113. This movement allows the released tension of the spring pressed 40 roller 166 to rock the levers 98 and 100 in a clockwise direction (Figs. 2 and 3) which serves to shift the valve stem 97 toward the left so that fluid under pressure passes through the pipe 93 into the valve chamber 94, passing outwardly 45 through the pipe 43, into the cylinder chamber 44, to move the piston 40 and the table 11 toward the right to bring the first cam on the camshaft 26 into operative grinding relation with the grinding wheel 16. Upon starting longitudinal movement of the table 11, a dog 321 moves out of contact with a rod 322 to close a limit switch 323 to 50 permit rotation of the headstock motor 280. Before the first cam 26 comes into operative position, the operator must push button 340 to close a circuit and start work rotation. The longitudinal movement of the table 11 continues until the first dog 112 engages the dog lever 114, which serves to rock the lever 98 from the position 98a to the position 98, thereby moving the valve stem 55 97 toward the right (Fig. 2) to cut out fluid from the pipe 43 and thereby stop the movement of table 11. During the movement of the lever 98 to the position illustrated in Fig. 2, the limit switch 305 closes, serving to energize the relay 306 which in turn energizes the solenoid 267 to bring the cycle control mechanism 245 to its initial position. 60

After the movement of lever 290 to the right to move the dog lever 114, the lever 290 is swung toward the left to start the grinding cycle, the pin 294 assuming position 294a. Upon further movement of table 11, the first dog 308a will disengage from plunger 309, allowing the limit switch 299 to close, and the solenoid 240 is energized to shift the wheel feed control valve 60 75

into the reverse position from that shown in Fig. 2, so as to admit fluid under pressure from the pipe 64, through the valve chamber 65, and through a pipe 56, into the cylinder chamber 57 to start the forward feeding movement of the wheel slide 15 and grinding wheel 16 and also to admit fluid under pressure through the pipe 237, into the chamber 236, to move the main control valve 175 toward the right (Fig. 2). The table 11 has traversed to the first table dog 112 before valve 175 covers the pipe 93. This movement of the main control valve 175 serves to cut out the flow of fluid through the pipe 93 to the table reversing valve 94 and serves to admit the flow of fluid under pressure through the pipe 132, into the cylinder chamber 133, to move the piston 128 toward the left (Fig. 2) which serves to rock the lever 120 in a clockwise direction and thereby serves to move the dog lever 114 out of the path of the table dog 112. At the same time the main control valve 175 is shifted, as above mentioned, fluid is allowed to exhaust from the cylinder chamber 90 to allow the rock bar 18 to rock so that the master cam 28 engages the master cam roller 29. Rotation of the master cam in contact with the master cam roller serves to rock the camshaft 26 to grind a cam blank to a predetermined contour. Each time the rock bar 18 rocks toward and from the grinding wheel, the cycle control counting device 245 is operated and the link 252 and the bell crank 250—251 serves to rock the pawl to turn the ratchet wheel 246 until the striker 253 engages the lever 254 of the mercury switch 257 and thereby break the circuit, which serves to deenergize the relay 260 to break the circuit and deenergize the solenoid 248 which in turn releases the tension of the spring 234 to permit the wheel feed valve 60 to move into the full line position, as illustrated in Fig. 2. This movement of the wheel feed valve 60 allows fluid passing through the pipe 64 into the valve chamber 65 to pass out through a pipe 232, into the valve chamber 233 of the main control valve 175, to move the valve toward the left, into the position of the parts illustrated in Fig. 2. This movement of the main control valve 175 again opens the passage of fluid through the pipe 93 to the valve chamber 94, and allows it to pass out through the pipe 43, to the cylinder chamber 44, to again index the piston 40 and the table 11 longitudinally to present the next cam into operative relation with the grinding wheel 16. This cycle of operation is continued until each one of the successive cams on the product camshaft is ground to the desired contour and size.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

1. A cam grinding machine having a wheel slide, a work table and a rock bar each of which is operated by a separate fluid motor, a main control valve in control of the work table and rock bar motors, a second control valve in control of said wheel slide motor and main control valve, and a control mechanism operated in timed relation with the rotation of said work to actuate said second valve.
2. A cam grinding machine having a wheel slide, a work table and a rock bar each of which is operated by a separate fluid motor, a main control valve in control of the work table and rock bar motors, a feed control valve in control of said wheel slide motor and the main control valve, and a control mechanism actuated in timed relation with the rocking of said bar to shift said feed control valve after a predetermined grinding operation has been completed.
3. A cam grinding machine having a wheel slide, a work table and a rock bar each of which is operated by a separate fluid motor, a main control valve in control of the work table and rock bar motors, a feed control valve in control of said wheel slide motor and which also serves as a pilot valve to shift the main control valve, and a control mechanism actuated in timed relation with the rocking of said bar to shift said feed control valve after a predetermined grinding operation has been completed.
4. A cam grinding machine having a transversely movable wheel slide, a longitudinally movable work table and a rock bar each of which is operated by a separate fluid motor, a main control valve in control of the work table and rock bar motors, a feed control valve in control of said wheel slide motor and the main control valve, and a cycle control mechanism including a pawl and ratchet actuated by the movement of the rock bar to shift said feed control valve after a predetermined grinding operation has been completed.
5. A cam grinding machine having a transversely movable wheel slide, a longitudinally movable work table and a rock bar each of which is operated by a separate fluid motor, a main control valve in control of the work table and rock bar motors, a wheel feed control valve in control of said wheel slide motor and which also serves as a pilot valve to shift the main control valve, and a cycle control mechanism including a pawl and ratchet actuated in timed relation with the movement of the rock bar to shift said feed control valve after a predetermined grinding operation has been completed.
6. A cam grinding machine having a longitudinally movable work table and a rock bar to rotatably support a camshaft thereon, each of which is operated by a separate fluid motor, a main control valve in control of said motors, a transversely movable grinding wheel slide, a fluid motor to operate said slide, and a control valve for controlling said wheel motor, said valve being connected to serve as a pilot valve to actuate the main control valve.
7. A cam grinding machine comprising a longitudinally movable work table and a rock bar to rotatably support a camshaft thereon, each of which is operated by a separate fluid motor, a main control valve in control of said motors, a rotatable grinding wheel and a transversely movable slide therefor, a fluid motor to control the transverse feeding movement of said slide, a control valve to control said wheel feed motor, and connections between said control valve and the main control valve whereby the control valve serves as a pilot valve for actuating the main control valve.
8. A cam grinding machine comprising a longitudinally movable work table and a rock bar to rotatably support a camshaft thereon, each of which is operated by a separate fluid motor, a

main control valve in control of said motors, a rotatable grinding wheel and a transversely movable slide therefor, a fluid motor to control the transverse feeding movement of said slide, a control valve to control said wheel feed motor, and connections between said control valve and the main control valve whereby the control valve serves as a pilot valve for actuating the main control valve, said valves and connections being 5 so arranged that the grinding wheel is withdrawn from engagement with the work before the bar is rocked to an inoperative position and before the table traverse is moved longitudinally.

9. A cam grinding machine having a transversely movable rotatable grinding wheel and supporting slide, a longitudinally movable work table and a rock bar, each of which is operated by a separate fluid motor, a main control valve in control of said work table and rock bar motors, 10 a feed control valve in control of said wheel slide motor and arranged to actuate said main control valve, means including electrical solenoid to shift said feed control valve to cause a forward and rearward movement of the wheel slide, 15 and a cycle control mechanism including an electric switch which is actuated in timed relation with the rocking of said rock bar to deenergize said solenoid and shift the feed control valve after a predetermined grinding operation to cause 20 30 a rearward movement of the wheel slide.

10. A cam grinding machine having a longitudinally movable work table and a rock bar thereon for rotatably supporting a camshaft to be ground, each of which is operated by a separate fluid motor, a main control valve in control of said motors, means including a master cam and a follower to rock said bar to grind a predetermined contour on the cam blanks, a rotatable grinding wheel and a transversely movable 35 wheel slide therefor, a fluid motor for operating said grinding wheel slide, a control valve in control of said wheel feed motor and to control said main control valve, electrically actuated means including a solenoid to shift said feed control valve against the compression of a spring to cause a forward movement of the wheel slide, and a cycle control mechanism including a pawl and ratchet actuated electric switch which is actuated in timed relation with the oscillation of said 40 rock bar during grinding to deenergize said 45 solenoid.

11. A cam grinding machine having a longitudinally movable work table and a rock bar thereon for rotatably supporting a camshaft to be ground, each of which is operated by a separate fluid motor, a main control valve in control of said motors, a rotatable work support on said rock bar including a rotatable headstock spindle and a foot stock associated therewith, 50 means including a master cam and a follower to rock said bar to grind a predetermined contour on the cam blanks, a rotatable grinding wheel and a transversely movable wheel slide therefor, a fluid motor for operating said grinding wheel slide, a control valve in control of said wheel feed motor and to control said main control valve, electrically controlled means to shift said feed control valve to cause a forward or rearward movement of the wheel slide, and a cycle control mechanism actuated in timed relation with the 55 oscillation of said rock bar during grinding, and an electric switch actuated by said cycle control mechanism to actuate said electrically controlled means and shift the feed control valve after a 60 predetermined grinding operation to cause a 65 70 75

rearward movement of the grinding wheel and a shifting of the main control valve.

12. A cam grinding machine having a longitudinally movable work table and a rock bar thereon for rotatably supporting a camshaft to be ground, each of which is operated by a separate fluid motor, a main control valve in control of said motors, a rotatable work support on said rock bar including a rotatable headstock spindle and a footstock associated therewith, means including a master cam and a follower to rock said bar to grind a predetermined contour on the cam blanks, a rotatable grinding wheel and a transversely movable wheel slide therefor, a fluid motor for operating said grinding wheel slide, a control valve in control of said wheel feed motor and to control said main control valve, electrical solenoid to shift said feed control valve to cause an infeeding movement of the wheel slide, yieldable means to shift said feed control valve to cause a rearward feeding movement of the grinding wheel, and a cycle control mechanism comprising a pawl and ratchet mechanism actuated by the oscillation of said rock bar during grinding, and an electric switch actuated by said pawl and ratchet mechanism after a predetermined grinding operation to deenergize said solenoid and release said yieldable means to shift the feed control valve to cause a rearward movement of the grinding wheel and a shifting of the main control valve. 10 15 20 25 30

13. A cam grinding machine having a longitudinally movable work table and a rock bar thereon for rotatably supporting a camshaft to be ground, each of which is operated by a separate fluid motor, a main control valve in control of said motors, a rotatable work support on said rock bar including a rotatable headstock spindle and a footstock associated therewith, means including a master cam and a follower to rock said bar to grind a predetermined contour on the cam blanks, a rotatable grinding wheel and a transversely movable wheel slide therefor, a fluid motor for operating said grinding wheel slide, a control valve in control of said wheel feed motor and to control said main control valve, electrical solenoid to shift said feed control valve to cause a forward movement of the wheel slide, a spring to shift the feed control valve to cause a rearward movement of the wheel slide, and a cycle control mechanism comprising a pawl and ratchet mechanism, connections between the pawl and ratchet mechanism and the rock bar, and an electric switch actuated by said pawl and ratchet mechanism after a predetermined grinding operation to deenergize said solenoid and thereby release the tension of a spring to shift the feed control valve to cause a rearward movement of the grinding wheel and a shifting of the main control valve. 35 40 45 50 55 60

14. A cam grinding machine having a wheel slide, a work table and a rock bar, each of which is operated by a separate fluid motor, a main control valve in control of the work table and rock bar motors, a second control valve in control of the wheel slide motor and the main control valve, manually operable means to actuate said second valve to manually control the cycle of operation, a control mechanism operated in timed relation with the work rotation to actuate said second valve automatically to control the cycle of operation, and connections which serve to render operative either the control mechanism for manually or automatically controlling the grinding cycle. 65 70 75 75

15. A cam grinding machine having a transversely movable wheel slide, a longitudinally movable work table and a rock bar, each of which is operated by a separate fluid motor, a main 5 control valve in control of the work table and rock bar motors, a control valve in control of the wheel slide motor and the main control valve, a manually operable lever to actuate said second control valve manually to control the grinding 10 cycle, a cycle control mechanism including a pawl and ratchet actuated by movement of the rock bar to shift the feed control valve after a predetermined grinding operation, and means including detachable connections which are arranged 15 to render either the manual control lever or the cycle control mechanism operative.

16. A cam grinding machine having a rotatable grinding wheel and a transversely movable slide therefor, a longitudinally movable work table 20 and a rock bar thereon, each of which is operated by a separate fluid motor, control valves to control the admission of fluid to said motors, a cycle control mechanism including an electric switch which is actuated in timed relation with the 25 rocking of said bar to control said valves, an electric limit switch in series with said cycle control mechanism, and a plurality of dogs on said table which are arranged to open said limit switch during the longitudinal traversing movement 30 of the table to render the cycle control mechanism inoperative.

17. A cam grinding machine having a rotatable grinding wheel and a transversely movable slide therefor, a longitudinally movable table and a 35 rock bar thereon, each of which is operated by a separate fluid motor, a main control valve in control of said table and rock bar motors, a feed control valve in control of said wheel slide motor and arranged to actuate said main control valve, electrically actuated means to shift said feed control valve to cause a rearward movement of the wheel slide and to shift said main control 40

valve, a cycle control mechanism including an electric switch which is actuated in timed relation with the rocking of said bar to energize said solenoid and to shift the feed control valve after a predetermined grinding operation, a limit switch associated with said control mechanism, and means on said table to actuate said limit switch to render the cycle control mechanism inoperative during the longitudinal traversing movement of the work table. 5

18. A cam grinding machine having a rotatable grinding wheel and a transversely movable slide, a longitudinally movable work table and a rock bar, each of which is operated by a separate fluid motor, a main control valve in control of said work table and rock bar motors, a feed control valve in control of said wheel slide motor and arranged to actuate said main control valve, electrically actuated means to shift said feed control valve to cause a rearward movement of the wheel 20 slide, a cycle control mechanism including an electric switch which is actuated in timed relation with the rocking of said rock bar to energize said solenoid to shift the feed control valve after a predetermined grinding operation, a limit 25 switch connected in series with said cycle control mechanism, and means including dogs on said table to actuate said limit switch when the table is moved longitudinally to render said cycle control mechanism inoperative during the traversing movement of the table and thereby to prevent an infeeding movement of the grinding wheel. 30

19. A cam grinding machine having a wheel slide, a work table and a rock bar, each of which is operated by a separate fluid motor, a main control valve in control of the work table and rock bar motors, a second control valve in control of the wheel slide motor and the main control valve, and manually operable means to actuate said second valve manually to control the 40 cycle of operation. 35
